LOUD-SPEAKER CABINET

Edward F. Shaver, La Grange Park, and Ralph P. Glover,
La Grange, Ill., assignors to The Muter Company,
Chicago, Ill., a corporation of Illinois

Filed Apr. 2, 1959, Ser. No. 55,319

Term of patent 14 years

(Cl. D26—14)

Fig. 1

Fig. 2

Fig. 1 is a perspective view of a loud-speaker cabinet showing our new design;

Fig. 2 is a side elevational view, the opposite side being substantially a mirror image thereof;

Fig. 3 is a side view, partly in cross section;

Fig. 4 is a top view, partly in cross section, the cross section being taken at the line 4-4 of Fig. 3;

Fig. 5 is a cross section taken at the line 5-5 of Fig. 3; and

Fig. 6 is a cross section taken at the line 6-6 of Fig. 3. The essential features of our design reside in the portions shown in full lines.

We claim:
The ornamental design for a loud-speaker cabinet, substantially as shown and described.
